UNITED STATES PATENT OFFICE.

CARL O. LAWRENZ, OF CHICAGO, ILLINOIS.

CHECK PROTECTOR.

Application filed June 7, 1928. Serial No. 283,543.

This invention relates to improvements in check protectors.

The principal object of the invention is to provide an improved device of the class mentioned that can conveniently be carried in a pocket or purse for use when required.

A further more specific object is to provide a protector one form of which has a rotatable perforating wheel the handles or finger pieces of which are partially housed within recesses in the wheel to provide a relatively thin, compact device.

Other objects of the invention relate to various features of construction whereby a device is provided which can be manufactured at a cost of only a few cents and which will be effective in operation, not only in preventing the alteration of checks, but in safe-guarding the signature or other written portion of any document on which the device may be used.

In the drawings:

Figure 1 is an elevation of a device embodying the present invention.

Figure 2 is a side elevation thereof.

Figure 3 is a diametrical sectional view taken on the line 3—3 of Figure 2.

Figure 4 illustrates a modified form of device.

Figure 5 is a broken view of a perforating wheel of modified construction, and

Figure 6 is a sectional view taken on line 6—6 of Figure 5.

The form of the invention shown in Figures 1 to 3 inclusive comprises a perforating wheel indicated generally by the numeral 10. The wheel has a cylindrical flange 11 and an integral web 12 provided in its center with an opening for receiving a short shaft 13 which is preferable oppositely threaded at its ends. The threaded portions of the shaft are of slightly less diameter than the central cylindrical bearing portion, whereby shoulders 14, 14 are formed, as shown in Figure 3.

The finger pieces 15, 15 are tapped to receive the threaded ends of the shaft, and as they are screwed into position the shoulders 14 space the pieces to provide sufficient clearance to prevent binding of the same on the side walls of the wheel and also cause the pieces to frictionally lock in position.

As shown, the pieces 15 are housed within recesses 16, 16 in the wheel 10, the provision of which permits the use of finger pieces of sufficient thickness to accommodate adequately deep threaded holes for receiving the shaft,

whereby a device of sturdy construction is provided and of a relatively flat disk-like shape.

The periphery of the wheel 10 may be provided with numerous teeth or points 17 which will readily perforate a paper 18, as shown in Figure 3, as the wheel is rolled over it, or the wheel may have perforating projections of other configuration, such as the L shaped edges 19 shown in Figures 5 and 6.

In Figure 4 a wheel 20 is shown in which the finger pieces 21 are not housed as in the above described form of the invention, but are carried on the ends of the shaft 13 entirely exteriorly of the wheel. The shaft has shoulders 14, similar to the form described above, and may also have right and left threads for convenience in assembling the device. The finger pieces 21 are provided with finger recesses 22.

In use the protector is held firmly by the finger pieces, the wheel rotating on the shaft as the device is rolled across the portion of the check or other document to be protected against alteration, sufficient downward pressure being exerted to cause the projections to cut into the paper whereby subsequent erasures can not be made without mutilation.

Although I have shown and described certain features of the invention for the purpose of illustration, I do not wish to be restricted specifically thereto except where so limited by the appended claims.

What I claim is:

1. A device of the class described comprising a rotatable wheel having perforating projections on its periphery, an axial opening being provided in said wheel, a relatively rotatable shaft in said opening extending beyond both side walls of said wheel, and finger pieces secured to the ends of said shaft.

2. A device of the class described comprising a wheel having perforating projections on its periphery and having recesses in its opposite side walls, finger pieces housed in said recesses, and a shaft passing axially through said wheel and having its ends oppositely threaded one to each of said finger pieces.

3. A device of the class described comprising a rotatable perforating wheel having an axial opening, a shaft in said opening having its ends oppositely threaded and extending beyond the respective side walls of said wheel, said threaded portions of said shaft being of

reduced diameter whereby shoulders are provided, and finger pieces having threaded recesses of greater depth than the threaded portions of said shaft whereby said pieces can be turned onto said shaft into frictional engagement with said shoulders.

4. A device of the class described comprising a perforating wheel having an axial opening therethrough, a shaft extending through said opening and beyond the side

walls of said wheel, the ends of said shaft being reduced in diameter to form shoulders, and finger pieces having axial recesses for receiving said reduced portions of said shaft and being secured on said portions against the respective shoulders in spaced relation with respect to the adjacent side walls of said wheel.

CARL O. LAWRENZ.
